UNITED STATES PATENT OFFICE.

SETH A. LEONARD, OF CLEVELAND, OHIO.

RHEOSTAT.

No. 888,517.

Specification of Letters Patent.

Patented May 26, 1908.

Application filed June 17, 1907. Serial No. 379,300.

To all whom it may concern:

Be it known that I, SETH A. LEONARD, a citizen of the United States, residing at Cleveland, in the county of Cuyahoga and State of Ohio, have invented certain new and useful Improvements in Rheostats, and do declare that the following is a full, clear, and exact description of the invention, which will enable others skilled in the art to which it appertains to make and use the same.

My invention relates to rheostats, and the invention consists in the construction and arrangement of parts substantially as herein-after shown and described and more particularly pointed out in the claims.

My object is embodied in a rheostat comprising a series of resistance units electrically connected in multiple and individually constructed with relatively low ampere conductive capacities and for relatively high voltages, each unit being capable of taking the entire voltage on the line. The units of each set may have different conductive capacities or values from the other sets, or all may be equal, dependent upon the work called for.

In rheostats ordinarily, the smallest amount of wire is in circuit when the current is heaviest and which puts a heavy burden on that portion of the rheostat in use, especially as the cross sectional area of the wire is always fixed and invariable, whereas in my invention the opposite is true, because I place the greatest amount of wire in circuit both in cross section and length when the greatest amount of current is flowing, and thereby provide for increased radiating surfaces and increased current carrying capacity when most needed.

Burning out of any one unit will not affect the other units or place the rheostat out of commission, and this is one advantage in having a large number of units working in multiple when operating under heavy conditions. However, each unit is designed to carry the extreme voltage on the line and burning out thereof is reduced to a minimum. Compactness and economy in construction are other features in favor of my device, especially when capacity and wide range of use is taken into consideration. For storage battery work, it has a range hitherto deemed impossible, as the smallest sparking battery or the largest sized automobile-truck battery may be charged or discharged with one and the same device. The rheostat shown in the

drawings and as hereinafter described will successfully charge and discharge a few cells or many cells, say from two to forty-four cells of any of the common sizes of cells used in automobile work. Obviously, the resistance units may vary individually in capacity, or be combined differently in sets to meet different requirements, either in storage battery work or in reducing line voltage.

In the accompanying drawings, Figure 1 is a front view of my improved rheostat, and Fig. 2 is a sectional view thereof on line 2—2, Fig. 1. Fig. 3 is a cross sectional view through the central portion of the rheostat, and Fig. 4 is a plan view and section on line 4—4, Fig. 3. Fig. 5 is an enlarged face view of one of the resistance coil units, and Fig. 6 is a sectional elevation thereof. Fig. 7 is a diagrammatic view of the elementary parts of the rheostat and their electrical connections.

In detail, my invention comprises a rigid open work frame built up of vertical corner pieces 3 of angle iron rigidly united at different elevations by front and rear cross rods 4, and which rods provide supports for the ends of parallel bars 5 located at each side and in the center of the frame. Bars 5 have a series of side lugs 6 or walled slots 7 spaced apart thereon from end to end which provide lateral supports for flat plates 8 of asbestos, and which plates are further supported and held in place by longitudinal strips 9 screwed or otherwise fastened to either the top or bottom edge of bars 5. Double rows or sets of such asbestos plates 8 are thus supported at equal distances apart from front to rear of the frame and at two different elevations on said frame, and upon removal of pairs of strips 9, any one or all of plates 8 in any particular section may be removed or replaced.

Each plate 8 is notched or slotted at opposite edges, top and bottom, to provide supporting portions 9' for resistance coil 10 which is wound spirally upon said plate in a continuous manner, beginning at one side and top at a binding post 11 and then passing down to the bottom where a loop 12 of the coil is slipped over portion 9' before passing up on the opposite side of the plate to make a similar loop attachment at the top, and thence downward and up again in like manner and in zig zag formation until the end is reached at a second binding post 110

13 at the other end of plate 8. In other words, resistance coil 10 is a helical wire coil wound spirally as a continuous body upon and around flat plate 8 from end to end and with the windings spaced apart and out of contact, and wherever the coil passes over the edges of the flat plate a loop 12 of the coil is engaged with a projecting portion 9' to hold and fix each winding against lateral and longitudinal movement. Plates 8 are all wound in a similar manner and are of uniform size, but as shown in the drawings resistance coils 10 are alike only in part, being divided into three sets of coils 10 in which the units thereof are designated by *a*, *b* and *c*, respectively, see Fig. 7. The amount of wire in units *a* is much less than in units *b*, and the same is true comparatively of units *b* and *c*, and constructively, the difference lies in the diameters of the coils and in the gage of wire used, units *a* having a conductive capacity of one ampere of current each, units *b* two amperes, and units *c* three amperes. However, it must be understood that I do not wish to limit myself to the definite number or capacity of the different units or sets of units shown, as different requirements and conditions may be readily met by different combinations and arrangements of the units. To further this end, said units are interchangeable and removably and replaceably secured within the main frame.

Now, referring to the switch mechanism for the rheostat, a rotary switch 15 is mounted upon a projecting stud or bolt 16 secured to insulating base plate 17 located upon posts 3 at the front of the frame. Said switch is of semicircular outline and is provided with a series of spring pressed contact pins 18, one for each contact segment 19 arranged in a semi-circle on base plate 17 and numbering forty all told. Switch 15 may be rotated either to the right or to the left to make initial contact with either contact segment 19 at the end of the semi-circle or the succeeding segments next in line. Contact segments 19 are insulated one from another, and have separate electrical connections or wires 20 leading to the binding posts 11 of their corresponding resistance coil 10, and switch 15 has a single electrical lead or wire 21 connected with line terminal 22 on base plate 17. Coils 10 are connected in multiple and to that end, have a return wire 23 from their respective binding posts 13 on each plate 18 leading to line terminal 24 on base plate 17.

Referring to Fig. 7, it will be seen that the first twelve segments 19 at the left connect individually with the first set of coils or units *a* of one ampere each, and that the middle series of segments, fourteen in number, connect with the second set of coils or units *b* of two amperes each; and again, that the right

end series, also fourteen in number, connect with the third set of coils or units *c* of three amperes each. Reading from left to the right the values represented in segments 19 accumulate in single amperes, from one to twelve, inclusive, and then by twos to forty, and then by threes to eighty-two. Reading from the right to the left, or reversely to the former reading, the values sum up differently and are cumulatively reckoned in threes for the first fourteen segments, and then by twos, and finally by ones. Thus, the current may be gradually varied in different proportions, dependent upon whether switch 15 is rotated to the left or the right from starting position, and a relatively large and flexible range in amperage is thus obtained by a single switch and a limited number of working parts.

The resistance coils may all be alike, say of five ampere conducting capacities each, and any predetermined number thereof may be connected in multiple to gradually vary an electrical current under high voltage, and I have found that in this connection I can produce effects and obtain results hitherto considered impracticable in a commercial rheostat, especially in theatrical work and in connection with moving picture machines.

What I claim is:

1. In rheostats, a series of resistance units of the same conductive capacities, combined with a series of resistance units of different conductive capacities, all of said units being electrically connected in parallel, and a switch for all said units adapted to switch each unit in parallel and successively and from one series to another.

2. In rheostats, separate sets of resistance units electrically connected, the respective sets having units of different conductive capacities and the units of each set having the same conductive capacities, and all said units having relatively low ampere conducting capacities at relatively high voltage, in combination with a switch electrically connected in parallel with every unit in said respective sets and arranged to place part or all of said units in parallel circuit.

3. A rheostat comprising separate sets of resistance units electrically connected and having relatively greater conductive capacities increasing successively from one set to another, in combination with a rotating switch electrically connected in parallel with each unit of each set and arranged to switch in said units from the first to the last successively until all said units are in circuit in parallel.

4. In rheostats, a series of resistance units electrically connected in parallel and divided into sets of different conductive capacities with like units in each set, in combination with a rotary switch adapted to be either continuously rotated in one direction to place

each unit in each set successively and cumulatively in circuit or reversely rotated to vary the cumulative effect of said units.

5. In rheostats, a series of resistance units of variable individual conductive capacity electrically connected in parallel in sets of units of the same individual capacity, and said sets of units successively arranged in cumulative value, and a switch therefor adapted to throw either the lowest or the highest sets of units initially in circuit.

6. In rheostats, a main frame and a series of resistance units removably mounted thereon and comprising separate insulating plates having a spirally wound resistance coil wound spirally around said plate in continuing folds of equal length and on opposite sides thereof.

7. In rheostats, a main frame and a series of resistance units supported thereby, said units comprising separate flat plates of insulating material and helical resistance coils wound spirally about said plates in a continuous coil body with parallel portions of equal length on opposite sides thereof.

8. A resistance unit for rheostats comprising a flat insulating plate having edge projections and a helical resistance coil wound spirally thereon in a continuous body and having loops of said coil looped with said edge projections at each winding of the coil body to hold and fix each winding against lateral and longitudinal movement.

9. In rheostats, a main frame having a series of horizontal bars parallelly arranged at different elevations, and a series of resistance units mounted in parallel rows thereon and apart from one another, said units comprising flat plates and having helical resistance coils secured on opposite sides thereof.

10. In rheostats, a main frame comprising vertical standards, and a series of parallel supporting bars mounted thereon at different elevations and provided with grooved faces, in combination with resistance units com-

prising flat plates adapted to be removably seated within said grooved faces and helical coils spirally wound around said plates and having terminal binding posts for making detachable electrical connections for each unit.

50

11. In rheostats, a main frame having vertical corner pieces and cross rods connecting the same and parallel bars supported at different elevations by said rods, in combination with a set of flat plates removably secured at their edges between contiguous bars and having helical resistance coils spirally wound upon said plates.

55

12. In rheostats, a main frame and a series of resistance units comprising flat plates removably supported at their edges in rows thereon and helical resistance coils secured upon said plates, a rotating switch mounted upon said main frame having individual contacts for each resistance unit and electrically connected in parallel therewith and adapted to be continuously rotated in one direction or reversely for varying results.

60

13. In rheostats, a series of separate resistance coils of relatively low ampere conducting capacities arranged in sets of different unitary values, in combination with switch mechanism electrically connecting said coils in parallel and comprising a semi-circular series of contacts, one for each coil, and a rotatable switch having a semi-circular contact portion adapted to successively switch in all of said coils in parallel by rotating the same in either direction and whereby the cumulative effect of the current to be switched in may be varied dependent upon the initial direction of rotation of the said switch.

70

In testimony whereof I sign this specification in the presence of two witnesses.
